PORTABLE WASHING, STERILIZING, AND DRYING MACHINE

Ralph Rodriguez Torrent, Washington, D. C., and Chester N. Husman, Orlando, and Eugene K. Dyson, Gainesville, Fla.

Application May 22, 1953, Serial No. 356,724

2 Claims. (Cl. 68—20)

This invention relates to a portable clothing washing, sterilizing and drying machine.

The invention is more particularly concerned with a clothing washing, sterilizing and drying machine which is embodied in a small relatively light casing in the form of a traveling case whereby it is readily adapted to be carried with other luggage in the course of travel in business pursuits or on trips or vacations.

While it is recognized that the washing, sterilizing and drying of clothing presents no particular problem in the home, where in most instances provision is made for such purpose in the form of standard equipment, it is, however, recognized that much difficulty is experienced by transients, traveling people and vacationers also persons living in small or efficiency apartments, wherein conditions are such that clothing washing and drying facilities are not readily available. Particularly is this true with the case of traveling parents who have young children and it is known, require a relatively large supply of clean sterile diapers always on hand.

It is accordingly a primary object of the invention to provide a portable washing, sterilizing and drying machine, which, while being substantially compact, embodies all of the necessary mechanical structure required for the thorough washing, sterilizing and drying of clothing.

Recognizing the advantage of a portable washing, sterilizing and drying machine under the above noted conditions, it is apparent that such machine in use requires a clean water supply as well as a place for the discharge of the dirty water from the machine.

It is accordingly a further object of the invention to provide a portable washing, sterilizing and drying machine which is adapted for positioning on the top of a toilet flush tank and which embodies conduit connections for a suitable hose adapted to extend from a water faucet of a lavatory, usually disposed adjacent a toilet for the supply of clean water and a hose adapted to extend beneath the toilet seat for discharge of dirty water from the machine into the toilet bowl.

Other objects and advantages of the invention will become apparent in the course of the following detailed description, taken in connection with the accompanying drawings, wherein—

Fig. 1 is a top plan view of the improved portable washing, sterilizing and drying machine in accordance with a preferred structure embodiment thereof, with the lid omitted.

Fig. 2 is a vertical sectional view as observed in the planes of the irregular line 2—2 on Fig. 1.

Fig. 3 is a top plan view of the machine with the lid closed and on a substantially reduced scale.

Fig. 4 is an elevational view.

Fig. 5 is a front elevational view showing the machine in an operative position on the top of a toilet tank.

Fig. 6 is an elevational view of a dirty water discharge nozzle adapted to extend into a toilet bowl.

Fig. 7 is a fragmental sectional view of a toilet bowl

2

and seat showing the discharge nozzle in operative discharge position within the bowl, and beneath the seat.

Referring now in detail to the drawings, the carrying case is designated at 10 and which includes a main body 11 and a lid 12. The body 11 is of generally rectangular form and may be of approximate dimensions of 16" long, 8" wide and 10" high and it is preferably formed of plastic or a light weight metal, such as aluminum.

The lid 12 is hinged to the body 11 as at 13 and is latched to the top of the body when closed by three pressure latches 14, one at each end and one at the front side as is clearly indicated on the drawings.

The lid 12 is further provided with a carrying handle 15 which when not in use recedes into a depression 16 in the top wall of the lid and as clearly indicated in Fig. 3.

A tub 16 is disposed within the casing body 11 adjacent one end thereof and which is of a capacity of from 1 to 2 gallons of water, and which is also constructed of plastic or other light weight metallic material.

Disposed within the tub in co-axial relation thereto, is an agitator 17 consisting of four blades or wings 18 in right angularly disposed relation and each provided with a plurality of apertures 19.

The agitator 17 is suitably secured to a shaft 20 whose lower end is disposed within a gear box 21 which is supported on the bottom wall of the casing body 11 by means of suitable legs 22.

Disposed horizontally within the casing body 11 at the end thereof opposite the tub 16 is a chrome plated hardware cloth member 23 which provides a drying compartment 24 between the same and the lid 12.

Disposed immediately beneath the cloth 23 in parallel relation therewith is a protected heating element 25.

Disposed beneath the heating element 25 is a fan 26, operable by a motor 27 whose armature shaft 28 extends into the gear box 21. The gear box 21 is provided with multiple reduction gears and transmission gears (not shown) which afford a clockwise and counterclockwise motion to the agitator 17.

An ultra-violet tube 29 is installed underneath the lid 12 above the drying compartment 24 and may be controlled by a switch which turns it off when the lid is raised so as to protect the eyes of the operator.

The casing body 11, at one end thereof, and adjacent the bottom wall is provided with a recess opening outwardly as at 30.

A switch 31 is disposed within said recess for controlling the heater element 25 and the ultra-violet tube 29. A second switch 32 is disposed within said recess for controlling the motor 27.

Below the switches 31 and 32 is a knob 33 for controlling the clutch for the agitator 17.

A water inlet pipe 34 is disposed within the casing body 11 and has its inner end communicating with the tub 16 as indicated at 35. The outer end of the inlet pipe is provided with a hose coupling 36 of any well known type also disposed within the recess 30 and it will be seen that the switches 31 and 32, knob 33 and hose connection 36 are all accessible from the corresponding end of the casing while being within the general plane of the end wall.

The tub 16 is provided with a drain pipe 37 whose free end embodies a hose connection 38 of any well known type disposed within an externally accessible recess 39 in the opposite end wall of the casing body 11.

The drain pipe 37 is provided with a valve 40 which is controllable by a knob 40', also disposed within recess 39.

An overflow pipe 41 extends from adjacent the top of tub 16 into communication with the drain pipe 37. The casing body 11 is preferably provided with axially ad-

justable suction cups 42 for leveling and rigidly supporting the casing on the lid L of a flush tank T of a toilet including a bowl B and seat S.

In operation, the machine is placed upon the top of the toilet lid L as indicated in Fig. 5.

A suitable hose 43 which when not in use may normally be carried within the casing has one end thereof connected to the coupling 36 and the opposite end thereof connected with a faucet of a lavatory for the supply of fresh water to the tub 16.

A second hose 44 which also may be normally stored in the casing has one end thereof connected to the coupling 38. The opposite end of hose 44 is provided with a metallic water discharge nozzle 45 which, as shown in Figs. 6 and 7, is curved in edge view for hooking over the rim of the toilet bowl B beneath the seat S and which, in face view, flares outwardly into flat form, whereby to distribute the discharged water for minimizing noise within the bowl and for the effective and sanitary disposal of the dirty water from the tub.

From the above disclosure it should be appreciated that a portable clothing washing, sterilizing and drying machine is provided which is readily transportable with other luggage and which is capable of ready disposition for operation, and which furthermore, is of a construction whereby it is highly efficient in the washing, sterilizing and drying of clothing.

While we have disclosed our invention in accordance with a single specific structural embodiment thereof, it is to be understood that various changes in the size, shape and arrangement of parts may be resorted to without departing from the spirit of the invention and the scope of the appended claims.

What we claim, and desire to secure by U. S. Letters Patent is:

1. A portable, clothing washing, sterilizing and drying machine, comprising a casing, a tub disposed within the casing adjacent one end thereof, a drying compartment within the casing adjacent the opposite end thereof having a perforate bottom wall, an elongated transmission gear box disposed within the casing beneath said tub and said drying compartment and supported on the bottom wall of the casing, a rotatable shaft extending vertically from one end of said transmission gear box and axially within said tub, an agitator disposed within said tub and secured to said shaft, a motor supported within said casing beneath said drying compartment and having a vertical armature shaft extending into the other end of said transmission gear box, whereby said agitator is rotated by the motor, and a fan supported by the motor in a position beneath said perforate bottom wall of the drying compartment.
2. The structure according to claim 1, together with water inlet and drain pipes supported within the casing and communicating with the tub, a recess in each end wall of the casing in which the outer end of a respective pipe is disposed, and the outer ends of the pipes being provided with hose connections.
